WINDING DEVICE FOR THE MANUFACTURING OF BOXES, FOR INSTANCE THE OUTER
CASINGS OF PUSH BOXES AND SIMILAR ARTICLES

Application filed June 16, 1932, Serial No. 617,679, and in Germany January 30, 1931.

In machines for the manufacturing of boxes and similar articles of veneer, pasteboard or any other suitable material, generally a strip of veneer etc. is wound round a mandrel, the 5 cross sectional shape of which corresponds to the cross sectional shape of the box to be made. For holding the strip to the mandrel during the winding operation a jamming device is used consisting of a tongue, which is fixed 10 directly to the mandrel in a swingable manner. The said tongue must be comparatively thin, because the veneer strip generally is wound through more than one revolution round the mandrel and consequently covers 15 the tongue. For practical reasons, for instance for the obviating of a great length of the mandrel and the unreliable journaling of the mandrel resulting therefrom, and also for causing the tongue to firmly clasp the strip 20 and thus to cause the same to accompany the mandrel in a reliable manner when rotated, the swinging axis of the tongue must be located as nearly as possible to the inner limit 25 of the path of the veneer strip. Practical experiments now have proved, that the said 30 journaling of the tongue involves the drawback, that, if for some reason more than one veneer strip would simultaneously be placed between the mandrel and the tongue, the 35 tongue brought into its operative position forms a great angle outwards with the mandrel, whereby the free outer end of the tongue will be located at such a great distance from the mandrel, that when the ordinary smooth- 40 ing roller which forces the veneer strip and the paper against the mandrel, passes the tongue, the tongue either is made crooked or is subjected to such a straining by the said roller, that it is broken. 45 For the removing of the said disadvantage the tongue according to this invention is journalled in a yieldable carrier in such manner, that, when there is a plurality of veneer strips between the mandrel and the tongue the spindle 50 on which the tongue is journalled may be moved in a direction away from the mandrel, so that the tongue is not subjected to any too great straining and thus breaking of the same is obviated. 55 In the accompanying drawing a mandrel

is shown in a perspective view in Fig. 1 provided with holding device (tongue) arranged in accordance with one form of execution of the invention. Fig. 2 is a section on line A—B in Fig. 1. 55

The mandrel shown as an example in the drawing is adapted for the manufacturing of the outer casings for push boxes. The mandrel 1 is carried by the rotatable shaft 2. The tongue 3 forcing the veneer strip against the mandrel and holding the same is swingable on a pin 4, which is mounted in a fork-shaped carrier 5. The said carrier straddles the mandrel and is slidably mounted in grooves provided in the sides of the same. A screw-shaped spring 6 is mounted in a cavity in the mandrel and bears against the transverse part of the fork 5 and tends to move the fork 5 upwards. The said movement, however, is limited by a screw 7 screwed into the mandrel. 60 The tongue 3 is provided with the ordinary arm 8, which, when subjected to a pressure, forces the tongue 3 against the mandrel. The said pressure is effected by a projection 9 on a head 10, which is slidably but not rotatably mounted on the spindle 2. The said head 10 is shifted at the suitable moment and in the ordinary manner during the operation of the machine by a fork-shaped member (not shown), which engages a circular groove 11 65 provided in the head 10. 70

If a plurality of veneer-strips would be simultaneously introduced into the space between the mandrel 1 and the tongue 3, so is the tongue when swung toward the mandrel 85 through the action of the projection 9 on the arm 8, forced against the said veneer strips, but instead of being subjected to a too great bending straining, the fork-shaped carrier 5 is forced downwards against the action of the spring 6, so that the pin 4 on which the tongue is mounted is lowered. Owing to this fact the tongue 3 will not be subjected to any bending straining and consequently there is 90 no risk of the tongue being broken. The elasticity of the spring 6 is so adapted, that it is somewhat slighter than the elasticity of the spring 3, so that there is a guarantee of the carrier 5 being lowered without the 95 100

tongue being subjected to a bending strain-
ing.

The tension of the spring 6 and the position
of the tongue may be suitably adjusted by
means of the screw 7. The fork-shaped head
carrier 5 is guided by the mandrel, while
forced downwards, and in this manner the
tongue is prevented from occupying any
oblique position transversely.

10 The invention may, evidently be applied
also to other machines provided with a man-
drel or any similar device and with a jamming
member, for instance to machines for the
manufacturing of capsules, tubes of paper
15 and the like.

I claim:

1. In a winding device for the manufac-
turing of boxes for instance the outer casings
of push boxes and similar articles the com-
20 bination of a mandrel, a jamming member
for holding the blank of the box, and a car-
rier for the said jamming member, which
carrier, is slidably and yieldably mounted on
the mandrel, transversely of the same.

25 2. In a winding device for the manufac-
turing of boxes, for instance the outer casings
of push boxes and similar articles, the com-
bination of a mandrel, a jamming member
30 for holding the blank of the box, a fork-
shaped carrier for the said jamming mem-
ber, which carrier straddles the mandrel and
is guided by the same, a spring actuating the
said carrier, and an abutment for the car-
rier, controlling the position of the same.

35 In testimony whereof I have hereunto af-
fixed my signature.

BROR ANDERS EMIL JOHNSON.
